UNITED STATES PATENT OFFICE.

OSCAR ANDREW RITZMAN, OF SUPERIOR, WISCONSIN.

KICKING-SLEIGH.

No. 841,447.

Specification of Letters Patent.

Patented Jan. 15, 1907.

Application filed November 9, 1905. Serial No. 286,627.

To all whom it may concern:

Be it known that I, OSCAR ANDREW RITZMAN, a citizen of the United States, residing at Superior, in the county of Douglas and State of Wisconsin, have invented a new and useful Improvement in Kicking-Sleighs, of which the following is a specification.

This invention relates generally to sleds, and more particularly to that class thereof known as "kicking-sleds," in which the sled with one rider thereon is pushed forward by the second rider, one foot resting upon one of the runners, while the other foot is employed for kicking or pushing the sled forward, and the sled is also steered by the foot.

The object of my invention is to provide a sled of this kind which shall be simple in construction and exceedingly strong and durable, the curved portion of the runners being specially constructed with strength and durability in view.

The invention consists in the novel features of construction hereinafter fully described, and pointed out in the claims.

In the drawings forming a part of this specification, Figure 1 is a perspective view of a sled constructed in accordance with my invention. Fig. 2 is a side view of the same. Fig. 3 is a detail side view of one of the runners before the forward end is curved or bent.

In constructing a sled in accordance with my invention I employ the two runners A, connected at their forward ends by means of cross-piece B in a manner hereinafter more fully described. Standards C are rigidly secured to the runners A and are connected intermediate their ends by means of a cross-bar D and at their upper ends by means of the handle E.

Beams F extend from the cross-bar D to the cross-piece B, and a block G is arranged upon said beams F adjacent their rear ends, said block serving to support the seat H in a horizontal position, the rear end of said seat being mortised in the cross-bar D. Iron braces I extend from the runners to the standard C, and similar braces K extend from the runners to the beams F, supporting the seat H.

As before stated, the forward ends of the runners are specially constructed with the

object of securing a very strong and durable runner, and this I accomplish by taking a straight piece of timber and splitting the same at the forward end, as shown at A', the opposite sides of said split being recessed, as shown at A'', and it will be noted that said recesses are not in alinement with each other before the split end is bent or curved. When the said split or bent end is curved, the inner portion thereof will project slightly above the outer portion, and the two recesses A'' will be brought into alinement with each other, and the ends of the cross-piece B will fit into the said recess and securely hold the bent or curved end of the runner in such position, thereby providing a rigid structure at the forward end. The runners A are of course equipped with the usual construction of metal runners.

In operation the one rider will sit upon the seat H and the other will grasp the handle E with both hands and place one foot upon one runner and kick or push with the other foot, propelling the sled forward, and the steering of the sled can be accomplished by pushing or dragging of either foot upon the ground.

From the foregoing description, taken in connection with the accompanying drawings, it will be seen that I provide a simple and durable sled of the kind described, the forward portion of which is exceedingly strong and durable.

Having thus fully described my invention, what I claim as new, and desire to secure by Letters Patent, is—

1. A sled of the kind described comprising the runners curved upwardly and split at their forward ends having recesses formed on the opposite faces of the split and connected by means of the cross-piece fitting in said recesses, the upright standards and cross-bar connecting the same, the beams extending from the cross-bar to the cross-piece, seat connected to the cross-bar and the block arranged upon the beams and beneath the forward end of the seat as set forth.

2. A sled of the kind described comprising the runners, standards, handle connecting the standards, cross-bar connecting the standards intermediate their ends, the cross-piece connecting the runners, the beams con-

necting the cross-piece and cross-bar and the seat supported thereon, the forward ends of the runners being split, the opposing faces of the split being recessed, said recess being arranged in such a manner that when the forward end of the runner is curved upwardly, the recesses are brought into alinement, the

ends of the cross-piece fitting into the alining recesses as set forth.

OSCAR ANDREW RITZMAN.
